CLARENCE R. DUERS, OF GLENS FALLS, NEW YORK, ASSIGNOR TO DUERS SIGNAL COMPANY, INC., OF GLENS FALLS, NEW YORK

ELECTRICALLY OPERATED WHISTLE

Application filed November 23, 1929. Serial No. 409,278.

This invention is directed to an improvement in electrically operated signals designed more particularly for use in connection with traffic controlling lights, whereby the change 5 of the light signals or of a particular light signal may be audibly indicated.

In controlling traffic by signal lights, the conventional system involves a green light to indicate a "go" signal, a red light to indicate a "stop" signal, and an amber light which provides a short period between the change of signals during which traffic is to be controlled by the immediately preceding signal. Thus, where the green signal has 10 been superseded by the amber signal, traffic is permitted to travel in the direction of the previous green signal until the stop signal is flashed, but frequently the motorist approaching a crossing is unaware as to 15 whether the amber signal showing is to be followed by a red or stop signal or a green or go signal, and at times there results a complication in traffic which leads to accidents or at least confusion. If an audible signal is 20 sounded as the amber light appears which is to be followed by a stop signal, the motorist is at once advised audibly that he is attempting to cross in the face of an immediately 25 imminent stop signal and can govern himself accordingly.

The primary object of the present invention, therefore, is to provide a unit self-contained device which may be connected in circuit with the amber signal, or in fact with 30 any of the signals, to audibly sound an alarm which will indicate to the oncoming motorist a particular signalling condition.

The invention consists in providing one or more signals, preferably so constructed as to 35 simulate in sound the ordinary traffic officer's warning signal, with these signals operated by air under pressure inaugurated through the movement of a piston which in turn is actuated through the energization of a solenoid, the movable core of which is connected to the piston.

It is well understood that it has heretofore been proposed to electrically operate signals by air under pressure with the air pressure 40 produced through electrically controlled

means, and the present invention is directed primarily to a construction which will permit of a simple, complete, self-contained unitary structure which may be readily associated with the usual signal poles and which, 55 when in position, requires merely the connection necessary to maintain the continuity of the electric circuit to the signal.

The invention is illustrated in the accompanying drawing, in which:

Figure 1 is a view in vertical section, partly in elevation, showing the construction of the improved signal, the parts being shown in inoperative or normal position.

Figure 2 is a similar view taken at right angles to the section of Figure 1, with the parts shown in operative position.

The improved signal includes a barrel casing 1, preferably of cylindrical form, to the lower end of which is removably secured a dome-like closure 2 centrally formed with a threaded offset 3 whereby the signal as a whole may be removably supported on the light signal pole or on any independent support as may be desired. A pressure chamber 4 is secured upon the upper end of the barrel casing 1, this pressure chamber involving a cylindrical wall preferably of greater thickness than the wall of the casing 1, with its lower end of somewhat reduced diameter, as 50 at 5, to provide a shoulder 5' to rest upon the upper edge of the casing 1 and a projection 6 to fit within the upper end of the casing 1.

The lower end of the pressure chamber 40 is closed by a plate 7 having an exterior diameter corresponding to that of the reduced portion of the wall 4, the plate being removably secured to the lower edge of the wall 4. Secured upon the wall 4 and closing the upper end of the pressure chamber 45 55 is a plate 10 on which are secured signals 11. These signals are here shown as two in number and being of the whistle type, though of course it is to be understood that the signals may be arranged in any number and 60 constructed to produce any desired type of signal.

The signals are in communication with the pressure chamber 9 through openings 12 in the plate 10, and integral with the plate 10 65 70 75 80 85 90 95 100

and surroundings the signals is an annular wall 13 formed with openings 14 through which the sound waves produced by the signal are permitted to emerge. Carried by and 5 preferably integral with the wall 13 is a sound deflector 15 in the form of a canopy-like wall, the free margin of which overlies the openings 14 in spaced relation thereto and is turned downwardly, as indicated at 16. 10 The downturned portion of the deflector serves to direct downwardly the sound waves passing through the openings 14, to thereby render the sound distinctly audible in the immediate neighborhood of the signal without 15 permitting any undue spreading of the signal to distant points. The signal is thus confined substantially at the crossing point for which it is intended and is practically inaudible at neighboring crossing points, therefore 20 by causing the signal to control the traffic only at the particular crossing point at which it is located, thereby avoiding disturbance of signals at adjacent traffic points.

A hollow piston 17 is slidably mounted 25 within the pressure chamber 9. This piston is in the form of a flat plate having a more or less close sliding fit with the interior of the wall 4 in order that the piston may serve, when operated in one direction, to displace 30 the air in the pressure chamber through the signals 11. As the piston is designed to return to normal or inoperative position by gravity, it is important that the fit between the piston and wall 4 of the pressure chamber 35 avoid that frictional cooperation which would tend to retard the gravitational movement of the piston to normal position.

In order to provide for this ease of movement of the piston and at the same time insure 40 piston functions in the operative movement of the piston, the wall 4 on its inner surface and the immediately adjacent portion of the plate 7 are formed with an oil-receiving annular recess 18 of comparatively 45 shallow depth, the inner edge of which has a rising wall abutment 18'. The peripheral edge of the piston 17 is offset to provide an edge flange 17' in the plane of the bottom of the piston to cooperate with the recess 18.

The narrow marginal edge of the piston proper 50 seats in the annular channel 18 when the piston is in its lower or inoperative position and as this channel 18 serves for the reception of lubricating oil, it is apparent that as the piston rises, the peripheral edge thereof carries with it a film of oil which not only acts as an air seal between the edge of the piston and the surface of the wall 4, but also serves to lubricate the piston in its 55 movements and particularly affords a comparatively easy descending movement of the piston which, as stated, is under the influence of gravity of the parts alone.

The piston, of course, in its downward 60 movement tends to wipe the oil from the in-

ner surface of the wall 4 and return the same to the channel 18 and to the recess 19 in the bottom of the piston. There is thus maintained a thin film of oil on the bottom of the piston and on the peripheral edge thereof which insures an efficient air seal and a proper lubrication of the parts for all necessary operations.

The piston is provided with a central up-standing stem 20 and this stem is guided in a cylindrical guide 21 rising from the plate 10 and more or less accurately receiving the stem 20. The upper end of the guide 21 extends through an opening in the deflector 15, and is formed with an opening 22 in its upper end to permit the escape of air during the upward movement of the stem, said opening 22 also serving for the admission of air on the downward movement of the piston. A cap 23 is removably threaded into the opening in the upper end of the deflector to prevent the escape of the sound through such opening and complete the appearance of the structure.

A solenoid in the form of a coil 24 and a core 25 is provided, the coil being arranged 90 below and carried by the plate 7. The coil is preferably supported on a spool-like frame 26 which is removably bolted at 27 to the bottom of the plate 7, and the core 25 is provided with opposing bars 28 which extend 95 through an opening 29 in the plate 7 and are hingedly connected by a pin 30 to a boss 31 depending from the lower side of the piston 17. The opening being of sufficient diameter to permit the sliding movement of the bars 28 therethrough will of course provide for the reception of the boss 31 in the downward movement of the piston to thereby permit the piston to move downwardly into contact with the plate 7 at the lower limit of movement or 100 inoperative position of said piston.

The lower end of the frame 28 is provided with a terminal 32 adapted, when the core 105 is in lowered position and the coil deenergized, to engage the upper end of an adjusting member 33 in the form of a screw threaded in a cross bar 34 supported at 35 at the lower end of the casing 1. The dome closure 2 may be provided with an opening through 110 which the screw 33 is accessible for adjusting the height of the screw and thereby controlling the adjustment of the core to insure a completely responsive movement of the core in the energization of the coil. Furthermore, this screw may be utilized to limit the downward movement of the core, so as to reduce the maximum stroke of the piston and thereby 115 reduce the volume of sound of the signals, though ordinarily this adjustment is not necessary.

It will be apparent that upon energization of the coil 24, the core 25 will move upwardly carrying with it the piston 17 and forcing the air in the pressure chamber 9 under pressure through the signals 11. The 120

sound of the signals will pass through the openings 14 and be downwardly directed by the skirt 16 of the deflector 15 and thus confined within a comparatively limited area. 5 The core may be adjusted in its initial position relative to the coil to insure the most effective operation under the magnetic influence.

While the signal is primarily designed for 10 use in connection with intersection traffic control lights in which one of the lights, say the amber light, is in series with the signal so that the signal will sound an audible alarm at the flashing of the amber light, it will of course 15 be appreciated that the signal is a complete, wholly contained, independent unit and as such is designed for use wherever a signal may be desired or employed where a source of electric current is available.

20 The signal may be supported by any appropriate base and secured thereto in any desired way and may thus be adapted to form a component part of any other apparatus with which a signal is to be associated. Any type 25 of specific signal 11 may be employed so long as the same is operated by air under pressure.

The mounting of the parts is of importance, particularly in their relative connections, as thereby extreme ease and simplicity are afforded not only in assembling the parts but in separating the same to gain convenient access to the interior for the purposes of repair and replacement.

What is claimed to be new is:

25 1. A self-contained signaling unit formed to provide a pressure chamber in the upper portion thereof, electrically operated means for creating pressure within said chamber, a signal chamber arranged above the pressure chamber and including an annular wall, a signal in the signal chamber and in communication with the pressure chamber to be sounded on the generation of pressure in said pressure chamber, the annular wall of the 45 signal chamber being formed with an opening immediately adjacent the signal to form a restricted outlet for the sound waves from the signal, the signal chamber including a deflector extension projecting outwardly from the upper edge of the annular wall of the signal chamber, with the free edge of such deflector extending downwardly substantially parallel to the annular wall of the signal chamber and directly overlying the 55 opening in the annular wall whereby the sound from the signal is directed only through the opening in the annular wall and the sound waves immediately thereafter deflected downwardly into substantial parallelism with the annular wall.

60 2. A self-contained signaling element including a barrel, a pressure chamber formed with the upper end of the barrel, a piston operative in the chamber, electrically operated means arranged within the barrel below

the pressure chamber for operating the piston, a plate closing the upper end of the pressure chamber, signals carried by the plate and open to the pressure chamber, an annular wall rising from the plate and formed opposite each signal with a sound emitting opening to initially direct the sound waves from that signal, a deflector projecting laterally from the upper end of the annular wall with its free end turned downwardly in parallelism with the annular wall and overlying the sound emitting openings therein, a hollow cylindrical guide carried by the plate and extending upwardly between the signals, and a guide element carried by the piston and operative in said guide in the movement of the piston.

In testimony whereof I affix my signature.
